DEMONSTRATOR DISPLAY

Edward K. Ploner, Glencoe, and John J. Sigman, Chicago, Ill., assignors to Chicago Flexible Shaft Company, Chicago, Ill., a corporation of Illinois

Application November 1, 1940, Serial No. 363,856

4 Claims. (Cl. 35—50)

Our invention relates to improvements in equipment to be used in conjunction with electric shavers, sometimes known as dry shavers.

The operator of an electric shaver is often beset with numerous difficulties and inconveniences which our invention seeks to avoid. Although conventional bathroom facilities are highly desirable for shaving with an ordinary razor but are not required for an electric shaver, a frequent practice prior to our invention has been for the user to employ the bathroom for shaving. This practice deprives others of the use of the bathroom at an hour when, very often, several people wish to make their morning toilet. It is also objectionable because frequently the poor location of mirror and light tends to obstruct the operator's vision or casts shadows on the whiskered portion of his face. Also, where one wishes to use a mirror on a piece of furniture, such as a dresser, he experiences difficulty because the relative location of the mirror and outlet frequently is such that he cannot use the mirror conveniently, if at all, and still have the cord to his shaver plugged into the outlet. And, after completing his shave, the user is left to the alternatives of gathering up the cord and placing it and the shaver away in a box or drawer, or of leaving the shaver exposed to view. Either of these alternatives is objectionable since it is inconvenient to wind and rewind the cord, while if the cord is not put away the shaving quarters appear disorderly.

An object of our invention, is therefore, to provide a unitary device for increasing the convenience of the user of an electric shaver by providing an apparatus for neatly receiving an electric shaver when not in use, for concealing the attached cord when not in use and having means for withdrawing and retracting it, and having an improved combination of mirror and illuminating means for shaving.

Furthermore, in the demonstration of electric shavers on retail counters, it is especially desirable that improved shaving conditions be provided for the prospective customer in order to favorably impress him with the merits of the particular shaver being demonstrated. If there are several models of a single make, the particular line of goods may be more effectively displayed, especially in a limited space, by arranging the shavers in a group. It is, therefore, another object of our invention to provide an improved apparatus, for demonstrating one or a plurality of electric shavers, consisting of an attractive cabinet having individual reception means for the shavers and containing means adapted to illum-

nate the user's face when operating the shaver before a mirror and means through which individual cords attached to the shavers may be withdrawn from or retracted into the cabinet when a particular shaver is moved to or returned from an operating position.

Furthermore, if as heretofore, artificial illuminating means is placed near the plane of the mirror, such as on either side or beneath or behind it, the light interferes with the vision of the user since a portion of it strikes the eyes directly, causing a mild blinding that one counteracts by squinting and confining his eye movement within a range least affected by the light rays. In so avoiding the light, one is not free to observe closely all the whiskered portions of his face, with the result that his shave is not entirely satisfactory. Certain types of lighting arrangements also fail to illuminate portions of the face beneath the chin. It is, therefore, another object of our invention to provide a device for use in connection with electric shavers in which electrical illuminating means is spaced forwardly from an upright mirror and in such lower relation thereto that the light rays strike the user's face from beneath as he uses the mirror, and are reflected to the mirror, whereby the whiskered portions of his face, including the portions beneath his chin, will be well illuminated without the direct rays from the source striking the eyes.

Still another object of our invention is to provide a compact, neatly appearing, and portable accessory for electric shavers through which the user is provided with adequate light and mirror means for shaving and in which there are means for withdrawing the shaver cord, otherwise concealed, by pulling and selective release means for automatically retracting the cord.

A further object of the invention is the provision of a shaving cabinet having a novel spool structure for storing the cord of an electric shaver.

The invention is illustrated in the accompanying drawings, in which—

Fig. 1 is a top elevation of our invention showing the different shaver models seated in their respective recesses;

Fig. 2 is a top elevation of the base plate and apparatus mounted thereon, with the cover portion removed;

Fig. 3 is a wiring diagram of the shaver and electrical illuminating circuits;

Fig. 4 is a vertical, longitudinal section on the line 4—4 of Fig. 1;

Fig. 5 is a transverse section on the line 5—5 of Fig. 4, the cover portion being removed, and

Fig. 6 is a fragmentary end view of the reel support bracket.

Referring to the figures, a cover 6 and a base plate 7 comprise the cabinet portion of our invention. The cover 6 is in this instance of a one-piece, molded plastic construction. A top wall 8 of the cover 6 is of a generally rounded configuration, the curvature beginning at its rear portion and rounding downwardly to merge into the plane of the base 7, the side walls and rear wall 9 being substantially vertical. The rounded corners of the cover 6 and the curvature of the top wall 8 give a generally streamlined appearance to the cabinet. Suction cups 10 are secured to the corners of the base 7 to prevent sliding of the cabinet when placed upon a flat surface.

Opposed pairs of vertical bosses 11 and 12 are located on the inner sides of the side walls of the cover 6 being integral therewith. The bosses at their lower end portions contain internally threaded metal inserts into which screws 13 are entered for securing the base 7 to the cover. The invention contemplates means for carrying an electric shaver which may for some purposes be carried on the outside of the cabinet. In this particular embodiment, which is designed for display purposes, electric shavers 14 and 15 of different configurations and size seat in a parallel spaced relation within corresponding recesses integral with the top wall 8. The recesses are of a reverse configuration identical with that of the shaver to be placed therein and are of a depth sufficient to prevent slipping or removal of the shaver through inadvertent jarring of the cabinet, yet adequately displaying the same and permitting it to be easily grasped and lifted therefrom.

An additional substantially cylindrical recess 16 is provided at the rear of the cover 6 between the shavers 14 and 15. This recess contains a sponge 17 saturated with an antiseptic for sterilizing the heads 18 and 19 of the shavers. This is especially desirable where different persons use the same shaver, as where they are exhibited for demonstration on a store counter. In such a case, the operator merely removes a closure 21 of the recess 16 and rubs the shaving head into the sponge 17, replacing the closure thereafter.

In the front rounded portion of the top wall 8, an opening is provided over which a glass window 22 having the same curvature is fitted to transmit light for shaving. The window 22 is secured in place at its upper and lower edges by clamps 23 which are fastened to corresponding bosses 24 integral with the cover 6 by screws 25. A conventional electric light bulb 26 is located directly beneath the window 22, being mounted in a socket 27 that is secured to a bracket 28 extending upwardly from the base 7 to which it is fastened. Translucent glass is preferably used, either of a ground type or otherwise, in order to most effectively diffuse the light coming through the windows for better shaving illumination. This diffused light is directed upwardly to strike the user's face from beneath to illuminate the desired portion of the face. Lighting conditions often provided for shaving render it difficult, in that portions of the shaving area of the face are improperly lighted so that there are shadows or darkened areas, but it has been found that these are practically eliminated where the user's face is illuminated from beneath. This window 22 may be etched or painted

as an advertising display that is visible only when the bulb 26 is lighted or at all times.

A circular mirror 29 having a metal rim 30 and tiltable on pivots 31 of a yoke 32 is mounted at the extreme rear center portion of the cover 6. An L-shaped bracket 33 integral with the yoke 32 secured to the cover 6 by screw and nut 34 and 35 holds the yoke 32 in a rigid relationship with the cover 6. It should be clear that one spaced from the mirror 29 at a distance favorable for shaving with an electric shaver will have the whiskered portions of his face illuminated by the light rays directed upwardly through the window 22 from their source in the bulb 26 to light his face from beneath. Since the window 22 is spaced forwardly from the mirror 29, whereby his chin is disposed above it, the light rays will not strike his eyes directly to interfere with his vision.

Heat generated by the bulb 26 is dissipated through ducts provided by parallel slots formed by ribs 36 integral with the top wall 8. These ribs 36 located between the shavers 14 and 15 also serve an ornamental purpose.

In this instance the shavers 14 and 15 are adapted to remain within their recesses with their cords attached. Each shaver has its individual reel 37 and 38 for its cord, each consisting of a pair of fiber disks in a parallel spaced relationship mounted on hubs 39 and 41 of an insulation material, in abutment with shoulders 39a and 39b of the hubs, respectively. The reels 37 and 38 are concealed within the cover 6, being rotatably mounted on a shaft 42 that is supported by spacers 42a and 42b which are mounted at their outer end portions on the upwardly extending side arms of a U-shaped bracket 43 whose cross-portion 44 is secured to the base 7 by a method such as welding. One of a pair of washers 45 and 46 of a conducting metal and of a pair of reel contact drums 47 and 48 having outwardly extending flanges 50 are mounted on each end of the hub 39, being held together in an immovable relationship with one another by a bolt 49 having a hollow center and its nut 51. Rubber washers 52 and 52a insulate the bolt 49 and nut 51 from the contact drums 47 and 48. The bolt 49 is rotatably mounted on the floating shaft 42, which provides a turning axis for the assembly of the reel 37. A cord 53 of the shaver 15 consists of leads 54 and 55 which enter through holes in the reel disk 37 having their uninsulated end portions pressed between metallic washer 45 and contact drum 47 and between metallic washer 46 and contact drum 48, respectively, making electrical contact therewith. It is clear from this construction that the bolt 49 is insulated from the contact drums 47 and 48 and from the washers 45 and 46, so that there will be no electrical conductor making electrical contact between drum 47 and washer 45 and the opposite drum 48 and washer 46.

The mounting of the reel 38 is identical with that of the reel 37, a cord 53a being wound thereon as shown in Fig. 5. Reel 38 including its cups 56 and 57 and washers 58 and 59 are rotatably mounted on an adjacent portion of the floating shaft 42, the spacing between the two reels being maintained by the fiber washer 61. The shaft 42 is journaled within the spacers 42a and 42b which maintain the spacing of the reels 37 and 38 from the bracket arms 43. These spacers 42a and 42b are held in a non-rotatable relation with the bracket arms 43 by projecting end portions 62 which enter into corresponding slots in the brack-

et arms, the spacers being held therein by cotter keys 63. Coil springs 64 and 65 are mounted on the spacers 42a and 42b, respectively, one end portion of each spring being kinked in a hole in the spacer at its outer end, the other end being entered in a hole in the bolt 49. The springs 64 and 65 provide a means for retracting the cords 53 and 53a wound upon the reels 37 and 38, for as the cord is unwound from the reel, the springs are loaded so that upon release of the cord the reel will be urged in an opposite direction to rewind the cord thereon.

Ratchet means for controlling the retraction of the cords 53 and 53a is provided by wire pawls 66 and 67 which are urged by leaf-springs 68 into notches 69 spaced about the periphery of the reels 37 and 38. The pawls 66 and 67 have outwardly extending right-angled end portions at each end, one such end portion being adapted to engage the notches 69 on the reels 37 and 38, the other ends being mounted for hinged movement in a vertical plane on the base 7 in bearings 66a and 67a, respectively. The leaf-spring 68 for each pawl 66 and 67 is mounted by rivets 71 to the base 7 so as to constantly exert an upward force against the pawls by which the spring is urged into the notches 69. A release means for disengaging the pawls 66 and 67 from the reels 37 and 38 is provided through the plunger 72 having an upper end portion that projects above the top wall 8 on which a cap 73 is mounted. The plunger 72 is slidably mounted in a boss 74 integral with the cover 6 so that when it is pressed downwardly its lower end portion on which a washer 75 is secured will force the pawls 66 and 67 downwardly to disengage them from the reels 37 and 38. If the plunger 72 is pressed downwardly by the operator when one or both of the cords 53 and 53a have been wholly or partly unwound from the reels 37 and 38, the reels will be released from the pawls, permitting them to turn in response to the urging of coil springs 64 and 65 to rewind the shaver cords 53 and 53a.

Wire loops 70 and pulleys 76 and 76a mounted on blocks 77 and 77a guide the respective cords 53 and 53a from the reels 37 and 38 upwardly through openings 78 and 79 in the top wall 8, thereby contributing to the ease with which the cords are wound and unwound from the reels.

The wiring diagram of my invention is shown in Fig. 3. Bars 81, 82, and 83 of a conducting metal, such as a copper alloy, are secured at one end to a bracket 84 having a center cross-piece spaced upwardly from the base 7, its vertical end portions terminating in the base 7 and being secured thereto. Rivets 85 and insulating washers 86 secure each of the bars 81, 82, and 83 to the cross-piece of the bracket 84. As is clear from Fig. 2, the blades 81 and 83 make electrical contact with the contact drums 47 and 57, respectively, being tensioned to contact the drums at a tangential relationship in any axial position. Blade 82 having forks 82a and 82b engages the inner drums 48 and 56 of the reels 37 and 38. As has been mentioned, the two leads of each cord 53 and 53a terminate in the drums on opposite sides of each of the reels 37 and 38, making electrical contact therewith. The circuit to shaver 14 is completed by the power lead 87 through the blade 83, the leads of the cord 53a, the fork 82a of blade 82, and power lead 88; while the circuit to shaver 15 is through power lead 88, fork 82b of blade 82, leads 54 and 55 in the cord 53, blade 81, and power lead 87. Leads 89 and 91 of the light bulb 26 are tapped in parallel into the power

leads 87 and 88. A switch 92 located on the top wall 8 of the cover 6 controls the power circuit to the shaver 15, the shaver 14 having its own switch control. The bulb 26 is lit continuously to make the display more attractive.

In operation, the user selects one of the shavers, lifting it from out of its recess and pulling its cord out to the desired length. This causes the cord to unwind from the reel and simultaneously to load the respective pull-back spring, such as spring 64. Retraction of the cord is prevented by the pawl and ratchet mechanism provided by the notches 69 on the reels and one of the pawls 66 and 67, its free end being urged into a notch 69 by leaf-spring 68. The user is now free to sterilize the shaving head by rubbing it in the antiseptic saturated sponge 11 and begin shaving. If shaver 15 is selected, switch 92 must be closed to complete the electrical circuit thereto. The mirror 29 is tilted so that he may shave under the most favorable light conditions furnished by the rays of the bulb 26 which are diffused as they pass through the window 22. Having completed his shave, the user presses the knob 73 on the plunger 72, causing one of the pawls 66 or 67 to disengage from the notch 69 permitting the reel to turn in response to the urging of the loaded coil spring and rewind the cord thereon. The user then replaces the shaver in its recess.

Various modifications may be made in the device embodying our invention without departing from the spirit and scope thereof, and we desire, therefore, that only such limitations shall be placed thereon as are imposed by the prior art and the appended claims.

We claim:

1. The combination of an electric shaver having a flexible electric cord, a cabinet having a recess therein of the configuration of the electric shaver and being of a depth to prevent the shaver from sliding therefrom yet permitting it to be easily lifted from the cabinet for use, reel means within the cabinet upon which the cord of the shaver is wound and designed to permit the unreeling of the cord upon its being pulled by the user, spring means for normally urging the reel means in a direction to wind the cord thereon, controllable means for preventing the rewinding of the cord from any of a plurality of unreeled positions, and manual release means for releasing the last-mentioned means through which the cord may be rewound upon the reel by power supplied by the said spring means.

2. In a device for use with an electric shaver having a flexible power-supply cord, of a cabinet having an open top recess for holding an electric shaver, reel means within the said cabinet on which the cord of the shaver is wound, the said reel means being rotatably mounted on an axis, means for urging the said reel in a direction to wind the cord thereon, stop means for preventing the retraction of the said cord when it has been unwound from the said reel in taking the electric shaver from the cabinet with its cord attached, manually operative means for releasing the said reel means from the stop means to permit the automatic rewinding of the cord on the said reel means, an electric current supply circuit with which said shaver cord is connected, and electrical illuminating means connected with said circuit, said illuminating means located in the forward portion of the said cabinet through which light rays are directed upwardly to illuminate the face of the user of the electric shaver.

3. The combination with an electric shaver having a flexible cord containing leads through which power is supplied to the shaver, of a cabinet for holding the same, a reel means within the said cabinet on which the cord of the shaver is wound, means for urging the said reel in a direction to wind the cord thereon, stop means for preventing the retraction of the said cord when it has been unwound from the said reel in taking the electric shaver from the cabinet with its cord attached, manually operative means for releasing the said reel from the stop means to permit the automatic rewinding of the cord on the said reel, an electrical illuminating means within the said cabinet adapted to illuminate the user's face when operating the electric shaver before a mirror and an electric current supply circuit connecting the shaver cord and the illuminating means.

4. In a shaving cabinet for an electric shaver having a flexible power-supply cord, a reel consisting of a pair of disks in a substantially parallel spaced relationship, a hub having shoulders which the inner center portions of the disks abut, a pair of reel contact drums of a conducting met-

5 al mounted on the hub, their bottoms abutting the said disks, an electric cord consisting of two insulated leads wound upon the said reel, the hub end portions of the cord containing no insulation and extending through holes in the disks which comprise the reel, each terminating between each disk and drum on each side of the reel making electrical contact with the said drum, a pair of spring tensioned contact bars, each contacting one of the said drums in a tangential relationship making electrical contact therewith, power leads supplying current to the said contact bars, means for holding the drums and reel in an immovable relationship with the said hub, axis means making a rotatable mounting for the said hub, spring means for urging the reel in a direction to rewind the cord thereon, stop means for holding the said reel at any of a plurality of positions in which the cord is unwound, and manually operative means for releasing the last-mentioned means to permit the winding of a cord upon the said reel.
